UNITED STATES PATENT OFFICE.

CARLTON L. HOFF, OF YORK, AND MARTIN O. REHFUSS, OF PHILADELPHIA, PENNSYLVANIA, ASSIGNORS TO STANDARD CHAIN COMPANY, OF YORK, PENNSYLVANIA, A CORPORATION OF NEW JERSEY.

CHAIN-LINK-FORMING MACHINE.

976,568.

Specification of Letters Patent. Patented Nov. 22, 1910.

Application filed December 1, 1908. Serial No. 465,527.

To all whom it may concern:

Be it known that we, CARLTON L. HOFF, of York, York county, Pennsylvania, and MARTIN O. REHFUSS, of Philadelphia, Philadelphia county, Pennsylvania, have invented 5 certain new and useful Improvements in Chain-Link-Forming Machines; and we do hereby declare the following to be a full, clear, and exact description of the same, reference being had to the accompanying drawings, forming a part of this specification, and to the figures and letters of reference marked thereon.

This invention relates to machines for 15 forming links, etc., particularly chain links, from wire or long rods, the said links, etc., being of proper form for being subsequently welded as by an electric welding process, although they may be of a form to be utilized 20 as open links, if so desired.

The invention consists in certain novel 25 details of construction and combinations and arrangements of parts all as will be now described and pointed out particularly in the appended claims.

In the accompanying drawings: Figure 1 is a plan view of a machine embodying the 30 present improvements. Fig. 2 is a sectional elevation on the line 2—2, Fig. 1. Fig. 3 is a similar view on the line 3—3, Fig. 1. Fig. 4 is a detail elevation of the nose of the guiding stop for positioning the blank. Fig. 5 is a section on the line 5—5, Fig. 4. Fig. 6 is a plan view of the formers. Figs. 7 and 35 8 are diagrammatic views showing a link at different stages during its formation. Fig. 9 is a view of a link completely formed and ready to be closed and welded.

Similar letters of reference indicate like 40 parts in all of the views.

In the machine illustrated as an embodiment of the invention, the wire or rod is fed intermittently; at each intermission a section sufficient to form one link is cut off 45 and by suitable instrumentalities, herein-after designated generally as "formers" the ends of the section are bent into proper shape to form when brought together, one end of the link and as a subsequent step the 50 section is bent centrally into proper shape to form the sides and other end of the link. As adjuncts to the formers, the machine embodies means for positioning the blank or severed section of wire or rod, both longitudi-

nally and transversely to insure the proper 55 coöperation of the formers therewith.

The working parts of the machine illustrated are carried by a bed plate A, having at one side and the back drive shafts B, B' journaled in bearings α and connected by 60 bevel gears B². Power is transmitted to the shaft B through a gear wheel B³ with which a pinion on the power shaft B⁴ is adapted to mesh.

The rod or wire C is preferably fed into 65 the machine by a rotary segmental feeder D (Fig. 3) mounted on the shaft B' and adapted to coöperate with a rotary and preferably concentric feeder D' journaled below the shaft B'. The feeders are connected for 70 simultaneous rotation by gears D², and it is obvious that the length of the gripping face of the segmental feeder will determine the length of rod or wire fed at each revolution of the shaft. From the feeders the leading 75 end of the rod passes through a guideway in a cutter bearing E and is adapted to be severed into sections or blanks by an oscillatory cutter E' mounted on a rock shaft E², having an arm E³ coöperating with one arm 80 of a bell crank lever E⁴ (Figs. 1 and 2). The other arm of lever E⁴ is provided with a pin or roller working in a groove cam E⁵ on the shaft B' and the position of the cam with relation to the feeder D is such that 85 the cutter makes its operative stroke immediately after the feed movement of the rod has ceased.

At its forward end, the rod is adapted to be guided and positioned by a vertically 90 movable guiding stop F (Figs. 3, 4 and 5) forming a continuation of a plunger F' mounted in an adjustable bearing bracket F², and adapted to be operated by a pair of toggle arms f from the intermediate bearing 95 of which a connecting rod f' extends to an eccentric f² on the shaft B'. The guiding stop is formed with a channel F³ in one side, as best shown in Fig. 5, which receives the end of the rod before the blank is severed 100 and the walls of the channel are cut away on the dotted lines indicated in Fig. 5 from a point somewhat above the end of the stop, as shown in Fig. 4, thereby forming a shoulder F⁴ and an inclined face F⁵, and providing ample space for the close operation of the formers, as will be presently described.

When the blank is severed from the rod, it

drops down in position to be acted on by the formers, being guided at one end by the guiding stop and at the other end by guides g (Fig. 2), but should it catch or, for any reason, fail to drop at once, its downward movement is insured by a pair of depressing fingers G mounted on a rock shaft G' operated by a lever G^2 , one arm of which cooperates with a projection G^3 (Fig. 2) carried by a cam disk M^5 on shaft B .

The severed blank is received on the projecting ends h of the reciprocatory formers H , and is positioned longitudinally thereon with its end against the stop F by a positioning plunger K mounted to slide in the lower portion of the bearing E and operated by a rock shaft K' , having arms K^2 , K^3 , the latter having a roller bearing on the peripheral cam K^4 . The plunger is preferably advanced by a spring K^5 , and retracted by the said cam, the parts being timed to position the blank just prior to the gripping and forming of the same, the plunger and stop both being withdrawn in time to permit the end formers to act.

When properly positioned, the blank lies between the reciprocatory formers H and rotary formers M . The formers H are mounted on or constitute parts of slide H' mounted in ways H^2 on the bed and reciprocated by toggle arms H^3 . At their outer ends the toggle arms H^3 are connected with a rock shaft H^4 , having an arm H^5 provided with a roller or projection h^6 working in a cam groove h^6 in a cam disk H^6 . The formers H are grooved at h^7 to receive the blank, and are of proper shape to conform to the shape of the end bends of the blank as shown in Fig. 7.

The rotary or angularly movable end formers comprise grooved rollers M , journaled eccentrically on the ends of vertically arranged carriers M' , journaled in bearings in the bed and having crank arms M^2 at the lower ends from which connecting rods M^3 extend to the lower ends of levers M^4 having rollers or projections m^4 at the upper ends working in cam grooves m^5 in the cam disks M^6 mounted on the shaft B .

Before the rotary or angularly movable end formers M make the effective portion of their movement, the blank is clamped at the center between reciprocatory center formers or clamps N and N' , the clamp N being advanced slightly before the cooperating clamp N' . Clamp N is operated by an arm N^2 (Fig. 3) on the end of a rock shaft N^3 , and the latter at its opposite end carries an arm N^4 with which one arm of a bell crank lever N^5 (Figs. 1 and 3) cooperates, the opposite arm of said bell crank lever N^5 being provided with a roller or projection n^6 working in a groove cam N^6 on the shaft B' .

Clamp N' is a former in that the center

bend of the link is made around its forward end, for which purpose it is preferably of the shape shown in Fig. 2, *i. e.*, with a recess or undercut at n' into which the bent ends of the link may project.

Movement is imparted to the clamp N' through a link n^2 connected with one arm of a bell crank lever n^3 , the other arm of said lever being provided with a roller or projection n^4 working in a groove n^5 (Fig. 2) in a cam disk n^7 (Fig. 1) on the shaft B .

The cams for operating the clamps N , N' are shaped to first bring the clamps together, as shown in Fig. 7, and then to move the clamps in unison, and while still holding the blank, toward the right in Figs. 1, 6, 7 and 8, the latter movement of the clamps taking place after the rotary end formers have bent the ends of the blank around the formers H and have moved out of engagement therewith and the formers H have retreated far enough to relieve the blank. As the rotary formers M begin to move the adjustable side formers advance into position for giving the center bend to the blank when the latter is forced through between them, said side formers embodying rollers O journaled on the ends of levers O' , angularly adjustable and held by clamp screws O^2 on slide O^3 working in ways O^4 on the bed. The slide O^3 and side formers are operated by crank arms O^5 on rock shaft O^6 through intermediate links O^7 . The shaft O^6 is oscillated by a crank arm O^8 having a roller or projection working in a groove cam O^9 on the shaft B' .

In operation, the positioning devices including the blank depressing fingers, the plunger K and the guiding stop F are withdrawn when the formers begin to make their effective movements, although the blank may have been previously pressed against the rotary formers by the advance of the formers H , and if desired gripped between the clamps N and N' .

As soon as the formers H are in position and the center of the blank is supported by the clamps N , N' , the angularly movable formers bend the ends of the blank around the formers H , as indicated in Fig. 7, the continued movement of the angularly movable formers carrying them out of engagement with the said ends. During the forward movement of the rotary formers the side formers O move up into operative position, where they remain until the link is forced back between them.

The sides of the link are bent into position by the simultaneous movement of the clamps N and N' which begins when the ends of the blank are released from the formers M and H , thereby carrying or transferring the blank bodily through between the now stationary side formers O , as shown in Fig. 8. The formers O are set to cause

the ends of the blank to approach each other as closely as desired, usually so as to leave just sufficient space for the admission of another link. The ends of the link having 5 been brought together below the former N' the latter retreats from the clamp N and the link is free to drop from the machine.

During the final forming movement of 10 the link the end formers are returning to first position, and the former N' releases the link during the initial portion of its movement toward first position. Inasmuch as this return movement is rapid and the new section of rod may be fed while the 15 return movement is taking place, there is little time when the formers are idle and consequently successive links may be formed with great rapidity. With the machine shown a link is formed at each revolution 20 of the shafts.

By varying the curvature of the formers H and N' links of any desired width and end curvature may be formed, and hence 25 the machine is adapted for the formation of links for various uses when it is desired to have the opening or weld at the end, rather than in one side of the link.

Having thus described the invention, what we claim is:

30 1. A chain link forming machine embodying a pair of reciprocatory formers around which the ends of the blank are bent and a pair of angularly movable formers pivoted on fixed axes and coöperating with said reciprocatory formers to simultaneously bend the ends of the blank and coöperating intermediate formers for bending the blank into link form.

2. A chain link forming mechanism embodying means for holding a substantially straight blank, angularly movable formers coöperating with and moving around the ends of the blank to bend said ends in the same direction and move out of engagement 45 therewith and means for moving the blank between and out of engagement with the angularly movable formers, and means independent of said formers for imparting an intermediate bend to the blank for bringing 50 the bent ends into proximity.

3. A chain link forming machine embodying oppositely arranged reciprocatory formers around which the ends of a blank may be bent, angularly movable formers mounted 55 eccentrically on fixed axes and adapted to travel around the ends of the first mentioned formers to bend the ends of the blank in the same direction, and means for clamping the blank centrally while its ends are being 60 bent and for moving the same bodily away from said end formers, and side formers between which the blank is moved for bringing the bent ends of the blank into proximity.

65 4. A chain link forming machine embody-

ing coöperating reciprocatory and angularly movable formers mounted on fixed axes for bending opposite ends of the blank simultaneously in the same direction, side formers and reciprocatory clamping formers with 70 means for moving the same toward and from each other to clamp and release the blank and for moving the reciprocatory clamping formers in unison in one direction to carry the blank bodily away from said end formers and between the side formers, whereby 75 its bent ends are brought into proximity.

5. A chain link forming machine embodying separated end formers and separated reciprocatory side formers movable toward 80 and from the end formers, and intermediate reciprocatory clamping formers movable past the side formers for transferring the blank from the end formers through and beyond the side formers.

6. A chain link forming machine embodying separated reciprocatory and angularly movable end formers and separated adjustable reciprocatory side formers and intermediate reciprocatory clamping formers 90 for transferring the blank from the end formers through and beyond the side formers.

7. A chain link forming machine embodying an intermittently acting rod feeding 95 mechanism, a cutter for severing the rod into blanks, reciprocatory end formers movable, projections for receiving the severed blanks, angularly movable end formers mounted eccentrically on fixed axes and 100 adapted to travel around the ends of the reciprocatory formers to simultaneously bend the ends of the blank, and intermediate formers for bending the blank centrally to bring the ends into proximity.

8. A chain link forming machine embodying an intermittently acting rod feeding mechanism, a cutter for severing the rod into blanks, reciprocatory end formers having projections movable therewith for receiving the blank, angularly movable end formers mounted eccentrically of their axes and adapted to travel around the ends of the reciprocatory formers to simultaneously bend the ends of the blank and reciprocatory 110 side and center formers for bending the blank centrally to bring the ends into proximity.

9. A chain link forming machine embodying an intermittently acting rod feeding 120 mechanism, a cutter for severing the rod into blanks, fingers for depressing the severed blank movable, projections for receiving the depressed blank, reciprocatory end formers around which the ends of the blank 125 are bent, angularly movable formers mounted eccentrically of their axes and adapted to travel around the ends of the first mentioned formers, side formers fixed with relation to each other and center blank clamping 130

formers movable between the end and side formers with means for operating said formers.

10. In a chain link forming machine, the combination with the end and intermediate formers and means for operating the same, of a reciprocatory guiding stop against which the end of the blank is positioned preliminary to the operation of the formers, 10 and a plunger for positioning the blank against the stop.

11. In a chain link forming machine, the combination with the end and intermediate formers and means for operating the same, 15 of the vertically movable guiding stop and the horizontally movable plunger between which the blank is positioned preliminary to the action of the formers.

12. In a chain link forming machine, the combination with the end and intermediate formers and means for operating the same, 20 of the guiding stop against which the blank is positioned, a spring pressed plunger for moving the blank against the stop and 25 means for withdrawing the plunger against the tension of its spring.

13. In a chain link forming machine, the

combination with the end and intermediate formers and means for operating the same, 30 of the reciprocatory guiding stop against which the blank is positioned, a spring-pressed plunger for moving the blank against the stop and means for withdrawing the plunger and stop from the paths of the formers during the operation of the latter. 35

14. In a chain link forming machine, the combination with the end and side formers, of center clamping formers one of which is provided with a blank engaging end face and a recess in rear of its blank engaging 40 face for the admission of the bent ends of the blank.

15. In a chain link forming machine, the combination with the formers and a rod feeding and cutting mechanism, of vertically arranged guides between which the cut blank is free to drop from the cutter to the formers and depressing fingers G for the purpose described. 45
